BUILDING BLOCK

Benjamin Liebowitz, New York, N. Y.

Application October 23, 1937, Serial No. 170,541

4 Claims.

(Cl. 72—44)

This invention relates to a building block, and more particularly to a precast unitary wall block of concrete or the like.

Walls made of the conventional concrete building blocks, either cored or solid, are not entirely satisfactory in that they do not afford proper insulation against heat and cold, and, furthermore, they do not adequately prevent seepage of water or moisture through the wall. It is well recognized that it is impractical to apply plaster directly on the inside of the masonry wall made of conventional blocks, as the plaster will show damp spots which tend to ruin it.

One proposal that has heretofore been made to overcome these defects of the conventional block is to construct a double wall of relatively narrower blocks arranged in parallel relation with an air space therebetween, the blocks of the two walls being tied together by wires or rods bent in substantially Z-shape and laid into the joints at intervals. For example, where an eight inch conventional block might be required to support a given load, a double wall can be used instead consisting of one three inch block and one four inch block spaced apart about two inches. Such double walls, while they improve the heat insulating properties and tend to prevent seepage of water and moisture, are relatively expensive both in labor and material. The cost of such double walls is normally at least about fifty per cent higher than that of a single wall composed of conventional blocks of comparable load bearing quality.

It is an object of my invention to provide a precast building block comprising two spaced longitudinal load-carrying members connected together by transversely extending integrally cast webs and reenforcing wires or rods, which block can be shipped, handled and set into the wall as a unit in the manner of the conventional building block.

Another object is to provide a building block for wall construction which will afford a high degree of heat insulation and will effectively prevent transmission or seepage of water or moisture through the wall.

A further object is to provide a reinforced block of the character described which can be readily fabricated in existing high production block casting machines.

A still further object is to provide a building block of such construction that the reinforcement may be easily and properly located and molded therein.

Other objects and advantages of the invention

will be apparent to those skilled in the art from the following description thereof, reference being had to the accompanying drawing, in which:

Figure 1 is a perspective view of the block;

Fig. 2 is an end view of the block;

Fig. 3 is a top plan view of the block.

Referring now to the drawing, my improved building block comprises two substantially parallel spaced longitudinal load-carrying members 10 and 11, having an air space 12 therebetween. Preferably, though not necessarily, one of these members is wider than the other, and the wider one, which in this instance is represented by the reference character 10, serves as the main load-carrying member. The opposed faces of the two members are slightly tapered to facilitate removal of the block from the core.

The members 10 and 11, which are made of concrete or the like, are joined at their lower portions, as shown in Figs. 1 and 2, by integrally cast transverse webs 13 of the same material. These webs may be disposed inwardly from the ends of the block and may be spaced from each other as seen in Fig. 3. It will be observed that the webs do not extend the full height of the block but only about one-half thereof so that the tops 14 of the webs are disposed a substantial distance below the top or load-bearing surface of the block. The lower faces 15 of the webs may be cut away as shown, although this is not essential.

In order to avoid any appreciable heat or moisture conduction from one member to the other, the connecting webs must have a minimum cross-sectional area. In the particular embodiment of the invention illustrated in the drawing, the cross-sectional area of the two webs combined is approximately eight to ten per cent of the face area of the block. While I have shown a block having two connecting webs, it is to be understood that one or more webs may be used depending upon the size of the block.

Web of such small size might not alone afford sufficient strength, and might cause trouble in casting, handling, and shipping the block. Therefore it is desirable to give the block additional strength by means of a metal reinforcement. To this end I reinforce the block with transversely extending wires or rods 16 that traverse the webs at or near their tops 14, and which are so shaped, as will hereinafter be described, that they may be properly located and supported in the mold used in casting the block. The reinforcements may consist of two separate transversely extending wires or rods, as shown,

or the wires or rods may be connected by longitudinally extending portions embedded in the members 10 and 11.

What I claim is:

- 5 1. A precast unitary building block of concrete or the like, comprising two spaced longitudinal members permanently connected at intervals by integrally cast transverse webs of relatively small cross-sectional area, the webs arranged at the lower half of the block thereby providing a clear space between the members at the upper half of the block throughout its length, reenforcing wires passing through the webs at their tops and having end portions which lie adjacent to one face of each of the longitudinal members.
- 10 2. A precast unitary building block of concrete or the like comprising two spaced longitudinal members permanently connected at intervals by integrally cast transverse webs of relatively small cross-sectional area, the webs arranged at the lower half of the block thereby providing a clear space between the members at the upper half of the block throughout its length, metal reinforcements lying within the block having portions that traverse the tops of the webs, and other portions that lie adjacent to the interior lateral faces of the longitudinal members.
- 15 3. A precast unitary building block of con-

crete or the like comprising a pair of substantially parallel longitudinal members permanently connected at spaced intervals along their lower portions by integrally cast transverse webs of relatively small cross-sectional area and of lesser height than the longitudinal members, the webs arranged at the lower half of the block thereby providing a clear space between the members at the upper half of the block throughout its length, reenforcing wires incorporated in the webs and the longitudinal members, said reenforcing wires having portions that pass through the tops of the webs and other portions that lie within the members closely adjacent their inner face portions and straddling the clear space between them.

10 4. A precast unitary building block of concrete or the like comprising a pair of parallel spaced members permanently connected by one or more small integrally cast webs and a metal reinforcement, the metal reinforcement being embedded in the parallel portions of the block above the tops of the webs and extending through the top of each web and having portions that lie closely adjacent to the inner opposed faces of the upper portions of the parallel members, the webs being arranged between the members at the lower half of the block.
